John P. Francis, 20 Boston St., Haverhill, Mass. 01830

Continuation-in-part of design application Ser. No. 179,248, Sept. 9, 1971. This application Sept. 27, 1971, Ser. No. 184,329

Term of patent 14 years

Int. Cl. D25—02

U.S. Cl. D13—1 M

FIG.1

FIG.2

FIG.3

FIG.4

FIG.5

FIG. 1 is a perspective view of a retractable window case structure and support therefor, embodying my new design.

FIG. 2 is a side elevation view, wherein the broken line illustration of the lower window sash is shown in contact with my new design.

FIG. 3 is a top plan view looking downwardly in the direction of the arrows 3-3 of FIG. 1.

FIG. 4 is a rear elevation view of the new design, and

FIG. 5 is a top plan view of a slightly modified form of the invention wherein a top cover is employed.

The window structure fragmentarily shown in broken lines in FIGS. 1, 2 and 3 is included for illustrative purposes only and forms no part of the claimed design.

This is a continuation-in-part of design application Ser. No. D. 179,248, filed Sept. 9, 1971.

I claim:

The ornamental design for a retractable window case structure and support therefor, substantially as shown and described.
